DOOR CLOSING CONTROL HINGE

Henry S. Diebel, Downey, Calif., assignor to
G. G. Bakewell, Pasadena, Calif.

Application August 19, 1946, Serial No. 691,557

4 Claims. (Cl. 16—50)

1

This invention relates to door closure control devices and in particular to means for hingedly mounting and controlling the opening and closing of a door.

One object of my invention is to provide a hinged closure control device embodying an actuating supporting hinge unit and a hinged hydraulic checking unit which, when used together on a door, coact to mount the door and to control the movement of the door so that it may be opened with little effort, following which it will smoothly, silently and automatically close when released. Another object is to provide hinges with interchangeable and removable cartridge-type control units concentric with hinge pins. Still another object is to provide a hinge having a removable cartridge-type coil-spring actuator unit. A further object of the invention is to provide a hinge having a removable cartridge-type hydraulic checking unit. Other objects are to provide hinge means for a hand operated door which control the rates of movement of the door in any part of its movement in either direction; to provide a non-leaking hydraulic control hinge which may be used for long periods of time without adjustment or servicing; to provide a spring actuating hinge arranged to carry the load of the door and having adjustable spring tensioning means so that it cooperates with the hydraulic hinge to control a particular door; to provide cartridge-type enclosures for both the actuating spring mechanism and the hydraulic control means to facilitate removal and replacement without removal of the hinge leaves and the cartridge-enclosing casings, from the door and the doorframe. These and other objects are attained by my invention which will be understood from the following description reference being made to the accompanying drawings in which:

Fig. 1 is a side elevational view partly in section and with parts broken away showing a weight-supporting actuating hinge;

Fig. 2 is a cross sectional view taken on the line 2—2 of Fig. 1;

Fig. 3 is a cross sectional view taken on the line 3—3 of Fig. 1;

Fig. 4 is a cross sectional view taken on the line 4—4 of Fig. 1;

Fig. 5 is a side elevational view of the cartridge unit containing a coil spring actuator mechanism;

Fig. 6 is a side elevational view partly in section with parts broken away showing an hydraulic checking hinge;

2

Fig. 7 is a side elevational view showing the cartridge containing an hydraulic checking mechanism.

Fig. 8 is a cross sectional view taken on the line 8—8 of Fig. 6;

Fig. 9 is a cross sectional view taken on the line 9—9 of Fig. 6;

Fig. 10 is a cross sectional view taken on the line 10—10 of Fig. 6;

Fig. 11 is a cross sectional view taken on the line 11—11 of Fig. 6;

Fig. 12 is a cross sectional view taken on the line 12—12 of Fig. 6;

Fig. 13 is a cross sectional view taken on the line 13—13 of Fig. 8;

Fig. 14 is a fragmentary view indicated by the line 14—14 of Fig. 6.

In general, my invention includes a pair of hinges adapted to hingedly mount a door on a doorframe, one of the hinges having an hydraulic checking mechanism for controlling the angular movement of the door and the other hinge having a coil spring actuator mechanism which is adapted to store up energy from the hand operation of opening the door and then to release the energy to actuate the door in the opposite direction, both the hydraulic checking mechanism and the spring actuator mechanism being separately enclosed in removable cartridges which are operatively encased in the cavities of the outer part-casings attached respectively to the two hinge leaves of each hinge, at least one hinge of each kind being used for each door mounting.

The actuating hinge is shown particularly in Figs. 1 to 5. Referring to these drawings, the actuator mechanism cartridge unit 20 consists of a cylindrical housing 21 having an integral flange 22 extending from its middle portion and having a hexagonal or other non-circular extension 23 of the hinge pin 24 from the upper end of the cartridge housing, the upper end of the cartridge housing being closed by a bushing 25 extending into the cartridge housing around the hinge pin 24, the bushing being non-rotatably attached to the housing. A sleeve bearing 26 is provided around the upper portion of the hinge pin within the cartridge housing 21, and between the hinge pin and said bushing. The hinge pin extends from the hexagonal extension 23 above mentioned through said bushing 25 to the opposite end of the cartridge housing where it is provided with an outwardly extending collar 27 upon which the lower end of the helical coil spring 28 may rest, the end of the coil spring being attached in a hole 30 in the hinge pin 24 above

the collar 27. The upper end 31 of the coil spring 28 is held in the hole 32 in the bushing 25, the hole and the end of the coil spring being long enough to permit some longitudinal dimensional change of the coil in the operations of winding and unwinding. The lower end of the hinge pin 24 is tapered to engage the inner ring 33 of the thrust ball-bearing unit 34, the outer casing thereof being adapted to fit snugly within the inner cylindrical wall of the cartridge housing 21, the ball bearing unit being held in place by the snap ring 36 placed in the groove 37 in the lower end of the cartridge housing 21. The flange 22 which is preferably made integrally with the cartridge housing in its middle portion is provided with radial holes 38 at spaced intervals around its circumference, and a headed pin 39 is provided to fit these holes, the head abutting the leaf 49 attached to the lower outer part-casing 48.

The upper leaf 40 of the actuator hinge is preferably made integrally with the outer part-casing 41 of the hinge, the said part-casing having a cavity 42 enclosing the portion of the cartridge housing 21 above the flange 22, and having a central hexagonal hole 43 in the upper end adapted to non-rotatably engage the hexagonal extension 23 of the hinge pin 24. The upper end of the part-casing above the hexagonal hole is provided with a threaded closure plug 44. A sleeve bearing 45 is provided between the inner wall of the part-casing 41 and the upper end of the cartridge housing 21 and a snap closing band 46 is conveniently provided over the holes 38 in the flange 22. The tension of the coil spring 28 may be regulated by positioning the pin 39 in the desired radial hole 38, the head of the pin 39 abutting the leaf 49 which is attached to the lower part-casing 48.

The lower part-casing 48 is preferably made integrally with the other leaf 49, and is provided with a cavity 50 adapted to fit outside the lower half of the cartridge housing 21. The angular movement of the hinge leaves 40 and 49 relative to each other causes the further winding up of the coil spring 28, and upon release, tends to force the leaves together angularly, the upper part-casing 41 rotating with the hinge pin 24 and the lower part-casing 48 moving with the cartridge housing 21.

The upper part-casing 41 with the upper leaf 40 may be adjusted vertically, relative to the lower part-casing 48 and its leaf 49 by means of the threaded plug 44 pressing upon the end of the hexagonal extension of the hinge pin, this adjustment being most important in the assembly of the actuator hinge with the hydraulic checking hinge on a door hingedly mounted on a doorframe, whereby the entire weight of the door may be carried on the thrust bearing 34. This arrangement has been found to be essential for the necessary functioning of the hydraulic checking hinge in the combination.

The hydraulic control hinge, which constitutes the subject matter of my divisional application Ser. No. 790,524, filed December 9, 1947, is shown particularly in Figs. 6 to 14, inclusive. The hydraulic mechanism is enclosed in the hydraulic cartridge unit 55 which consists of a cylindrical cartridge housing 56 which is provided in its central portion with an outwardly extending flange 57. The hexagonal extension 58 of the hinge pin 59 extends above the cap 60 which closes the upper end of the cartridge housing 56. In the

opposite end of the cartridge housing 56, there is provided a draw screw 61 for fastening the cartridge inside the outer casing as will be later described. The lower end 62 of the cartridge housing 56 is slightly tapered.

The hydraulic checking mechanism consists of a rotary piston 63 attached to the hinge pin 59 in a cylindrical working chamber 64 having a segmental partition member or dam 65. The working chamber 64 is formed by the inner surface of the cartridge housing 56, the radial ends of the dam 65, the bottom closing member 66 and the upper closing surface consisting of the bottom 67 of the reservoir bushing 68. A bearing for the lower end of the hinge pin 59 is formed by reducing the diameter of the hinge pin below the piston 63, to fit a hole in the closing member 66, the latter being supported on the bushing 108 which rests upon the draw ring 107 which serves as a closing member for the cartridge housing. The rotation of the hinge pin 59 causes the angular movement therewith of the rotary piston 63 in the working chamber 64 from one edge of the dam 65 to the other edge, the dam 65 extending between the wall of the cartridge housing 56 to the surface of the hinge pin. As the piston moves, the hydraulic fluid is forced through several controlled conduits which act to regulate the hydraulic friction in the movement of the hydraulic fluid from one side of the piston to the other. One control consists of metering pin 69 operating in a hole 70 concentric with and in the center of the hinge pin 59. At right angles to the hinge pin a bypass conduit 71 through the hinge pin is provided (see Fig. 9), the metering pin, in the portion adjacent the conduit 71, being tapered so that the flow of hydraulic fluid may be closely regulated by the endwise movement of the metering pin 69. The pin 69 is positioned by the threaded plug 72 which is threaded into a hole in the upper part of the hinge pin, the metering pin 69 being held upwardly by a compressed coil spring 73 in the bottom of the hole 70. A one-way bypass conduit from one side of the piston to the other is provided by the hole 74 leading through the hinge pin 59 from one side of the piston 63 to the other (see Fig. 10), the hole being provided with a ball 75 in a seat 76 and held in place by a retainer 77. When the piston 63 is moved counterclockwise (see Fig. 10) hydraulic liquid flows freely to the "closed" side of the working chamber C from the "open" side of the chamber O. When the piston is moved in the opposite direction, the ball 75 is forced into the seat 76 and shuts off the flow of hydraulic fluid. In the movement of the piston from O position to the C position, the flow of hydraulic fluid is further controlled by means of grooves of varying cross-sectional area, cut in the under surface 67 of the reservoir bottom which serves as the upper closing wall for the hydraulic working chamber. In the preferred arrangement, as shown, a by-pass groove 78 large enough to permit substantially unrestricted movement of the hydraulic fluid therethrough is provided in the first part of the movement of the piston (in the direction of closing the hinge) following which the groove is tapered to gradually retard the flow of hydraulic fluid by gradually decreasing the cross-sectional area; followed by a terminal groove 80 similar in cross-sectional area to the bypass groove 78, allowing free flow of hydraulic fluid. The arrangement of connected bypass grooves thus described provides for the initial unretarded closing of the hinge and the attached

door by the actuator hinge mechanism until the door approaches the fully closed position, at which point the constricted groove retards the flow of liquid and slows down the movement of the door, and then shortly before reaching the final closed position, the hydraulic resistance is removed by the provision of the large cross-sectional area 80 so that the actuator hinge forces the door into the latch in the fully closed position.

Provision is also made in the hydraulic unit for compensating for the difference in fluidity of the hydraulic liquid due to temperature changes. An auxiliary bypass hole 81 through the hinge pin 59 within the working chamber 64 is controlled by means of the thermostatically operated metering pin 82 which slides in a hole 83 in the lower portion of the hinge pin 59, and concentric therewith, a coil compression spring 84 being placed in the hole to act against the metering pin 82. A "sylphon" metallic bellows 85 containing a suitable fluid acts to move the metering pin in response to temperature changes. The bellows 85 is placed in a cavity in the bushings 108 adjacent the closing member 107. When the temperature rises, the thermostatically controlled metering pin closes off the auxiliary bypass hole 81, to compensate for the lower viscosity of the hydraulic liquid.

The non-pressured reserve hydraulic liquid reservoir 68 consists of an annular space between the reservoir bushing 68 and the hinge pin. The reservoir is connected hydraulically with the working chamber by means of check-valved orifices 86, one on each side of the piston. The reservoir bushing is held in place within the cartridge housing by means of locking rings 88 and 89. The top portion of the reservoir is closed by the closing cap 60, and a sleeve bearing 90 and 91 is provided between the hinge pin and the closing cap 60. A rubber O ring 92 being provided around the hinge pin between the bearings 90 and 91 to prevent leakage of hydraulic liquid. The radial position of the reservoir bushing is fixed by means of the key 93 in suitably placed holes in the reservoir bushing 68 and the dam 65. A closing cap 94 is provided at the upper end of the opening in the hexagonal extension 58 of the hinge pin 59.

The upper leaf 98 of the hydraulic hinge is made integrally with a part-casing 99 adapted to fit over the upper portion of the hydraulic mechanism cartridge housing 56. A sleeve bearing 95 is provided between the cartridge and the inner surface of the part-casing 99; and a hexagonal cavity 96 is provided in the upper end of the part-casing 99 adapted to non-rotatably engage the hexagonal shaft extension 58. The cap 94 threaded into a hole in the end of the shaft extension 58 is accessible through an opening in the upper end of the part-casing 99.

The lower leaf 100 is preferably made integrally with a lower part-casing 101 and is adapted to fit over the lower portion of the cartridge housing 56, the cavity of said lower part-casing being slightly tapered at the bottom to correspond to the tapered end portion 113 of the cartridge housing adjacent the draw screw 61, and the end of the lower part-casing is provided with a threaded hole 102 adapted to engage said tightening member 61, the draw screw 61 being provided with an hexagonal hole 103 adapted to be engaged by a hexagonal bar tool to turn the draw screw 61. The inner end of the draw screw 61 is provided with a head 104 having an underside

tapered edge face 105 which is adapted to engage a tapered hole 106 in the closing member 107 of the cartridge. The draw screw 61 may thus be used to draw the cartridge housing 56 into the lower part-casing 101 to hold the cartridge non-rotatably within the casing. A key 112 holds the closing member 107 and the dam 65 in alignment. When it is desired to remove the cartridge from the casing, the reverse turning of the draw screw 61 pushes the cartridge out of the tapered portion through pressure of the head 104 which abuts the bushing 108 containing the "sylphon" bellows 85.

In order to adjust the relative positions of the hinge pin and its attached leaf and the lower part-casing 101 and its attached leaf 100, provision is made for an index marking adjacent the flange 57 of the cartridge housing 56, as shown particularly in Fig. 14. A tool-receiving hole 109 is provided in the flange at a selected relative position for the two leaves of the hinge, for example at the closed position. Index marks 110 are made at either side of this hole to permit setting of the parts relative to the corresponding index marks 111 on the casing 101. This arrangement provides ready means for adjusting the position of a replaced cartridge in the casing after it has been removed for repair or renewal.

The advantages of my cartridge type hinges will be apparent. The cartridge unit, whether it contains the hydraulic checking unit or the actuator unit of the pair of hinges required to form a complete hinged door closer, may be readily removed without removal of the leaves attaching the hinge outer casings to the door and door-frame. The hinge outer casings may be ornamented or shaped as desired, while the cartridge type mechanisms for actuating and checking the door may be interchangeable.

I claim:

1. A hinge mechanism comprising a pair of leaves adapted for attachment to a closure and to a closure mounting frame; a cartridge having a cylindrical housing and a concentric shaft extension protruding from the upper end of said cartridge housing; a hollow upper part-casing extending from the edge of one leaf, adapted to fit over and turn on the upper portion of said cartridge housing, and to non-rotatably engage said shaft extension; a hollow lower part-casing extending from the edge of the other leaf, adapted to fit upon and be non-rotatably attached to the lower portion of said cartridge housing; and rotary motion means within said cartridge governing the turning of said shaft extension relative to said cartridge housing.

2. A hinge mechanism comprising a pair of leaves adapted for attachment to a closure and to a closure-mounting frame; a cartridge unit having a cylindrical housing; a shaft mounted coaxially therein with a shaft extension protruding from the upper end of said housing, said shaft being enclosed within said housing; a helical coil spring around said shaft, one end thereof being attached to said shaft and the other end being attached to said housing; a hollow upper part-casing extending from the edge of one leaf adapted to fit over and turn on the upper portion of said cartridge housing and to non-rotatably engage said shaft extension; and a hollow lower part-casing extending from the edge of the other leaf, adapted to fit upon and be non-rotatably connected to the lower portion of said cartridge housing.

3. A hinge mechanism comprising a pair of

leaves adapted for attachment to a closure and to a closure-mounting frame; a cartridge unit having a cylindrical housing; a shaft mounted coaxially therein with a shaft extension protruding from the upper end of said housing, said shaft being enclosed within said housing; a helical coil spring around said shaft, one end thereof being attached to said shaft and the other end being attached to said housing; a hollow upper part-casing extending from the edge of one leaf adapted to fit over and turn on the upper portion of said cartridge housing and to non-rotatably engage said shaft extension; a hollow lower part-casing extending from the edge of the other leaf, adapted to fit upon and be non-rotatably connected to the lower portion of said cartridge housing; and adjusting means manually operable when said hinge mechanism is in operative position mounting a door on a closure-mounting frame for longitudinally spacing said upper and lower part-casings relative to said cartridge unit, said means including a plug screw in said upper part-casing positioned to abut the upper end of said shaft extension.

4. A hinge mechanism comprising a pair of leaves adapted for attachment to a closure and to a closure-mounting frame; a cartridge unit having a cylindrical housing; a shaft mounted coaxially therein with a shaft extension protruding from the upper end of said housing, said shaft being enclosed within said housing; a helical coil spring around said shaft, one end thereof being attached to said shaft and the other end being attached to said housing; a hollow upper

part-casing extending from the edge of one leaf adapted to fit over and turn on the upper portion of said cartridge housing and to non-rotatably engage said shaft extension; a hollow lower part-casing extending from the edge of the other leaf, adapted to fit upon and be non-rotatably connected to the lower portion of said cartridge housing; and means for adjusting the tension on said coil accessible when said cartridge unit is in place within said upper and lower part-casings including radial holes in the periphery of said housing, a detent pin mounted in one of said holes, said pin in its extended portion outside said radial holes abutting the juncture of said leaf of said lower part-casing.
